[57] CLAIM

The ornamental design for a portable work table, substantially as shown and described.

DESCRIPTION

FIG. 1 is a top plan view of a portable work table showing our design;

FIG. 2 is a front elevation of the FIG. 1 platform; FIG. 3 is a left end elevation of the FIG. 1 platform, the right end elevation being the same;

FIG. 4 is a rear elevation of the FIG. 1 platform;

FIG. 5 is a bottom view of the FIG. 1 platform; and

FIG. 6 is a section on lines 6—6 of FIG. 1.

FIG. 2.

FIG. 3.

FIG. 4.

FIG. 5.

FIG. 6.
